(57) **CLAIM**

The ornamental design for a speaker for cars, as shown and described.

DESCRIPTION

FIG. 1 is a front perspective view of a speaker for cars showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right-side elevational view thereof; and,

FIG. 7 is a left-side elevational view thereof.

The broken lines shown in the drawings depict portions of the speaker for cars that form no part of the claimed design.

1 Claim, 7 Drawing Sheets
